Specification of Letters Patent.

Patented Jan. 8, 1918.

Application filed May 7, 1917. Serial No. 166,998.

To all whom it may concern:

Be it known that I, EDWARD H. CUMPSTON, Jr., of Rochester, in the county of Monroe and State of New York, have invented certain new and useful Improvements in Check-Writers; and I do hereby declare the following to be a full, clear, and exact description of the same, such as will enable any person skilled in the art to which the invention appertains to make and use the same.

The present invention relates to printing apparatus, and more particularly, to printing machines of the variety having a plurality of separate type forms adapted to be selectively employed to compose and print various desired combinations of characters, or legends.

One object of the invention is to provide a machine of the class described suitable for printing a range of legends, such, for instance, as monetary values, and so arranged that any desired legend, having once been selected, may be impressed on the work, as often as desired, with but a single printing operation for each impression.

Another object is to provide a simple and convenient machine of this character having available a plurality of type forms of various lengths adapted to be selectively combined for printing a series of legends, with arrangements for impressing a selected legend upon the work by a single printing operation in such manner that the several characters of the legend will be printed in line with a small, uniform spacing distance between the adjacent words or characters.

Another object is to provide such a machine in which the type forms required for printing a legend may be conveniently assembled in line in printing position with various spaces between them, but printed in line on the work with small, equal spacing distances between adjacent words or characters.

These and other objects and advantages will more fully appear from the following detailed description of one embodiment of the invention, selected for purpose of illustration, and shown in the accompanying drawings, in which—

Figure 1 is a front elevation of the machine.

Fig. 2 is an enlarged elevation from the front of the machine, partly in section or

the line 2—2 in Fig. 3 and partly broken away.

Fig. 3 is a sectional elevation on the line 3—3 in Fig. 2.

Fig. 4 is an end elevation of the machine.

Fig. 5 is a top plan view of the base portion of the machine, partly broken away, showing the printing bed and accessories.

Fig. 6 is a top plan view, partly broken away, of the reciprocating work support and related parts.

Fig. 7 is a rear elevation of the same, partly in section and partly broken away.

Fig. 8 is a front elevation of the same with parts broken away.

Fig. 9 is a top plan view of the presser foot and stripping plate for the work.

Fig. 10 is a top plan view of the cam for controlling the presser foot, taken on the line 10—10 in Fig. 3.

Fig. 11 illustrates an impression made by the machine.

In its present form the invention is embodied in a machine having an inclosing and supporting casing for the operating parts composed of a lower base portion 15 and an upper portion 16, these portions of the casing being partially separated by a work receiving slot 17, formed in the casing above the work bed 18 supported by the base portion of the casing.

The type forms are carried in the upper and overhanging portion 16 of the casing, to which end there is preferably provided a shaft 19 fixedly supported at its ends in the end walls of the casing. Rotatably supported on this shaft are a plurality of hubs 20 (Figs. 2 and 3), each having fixed thereon a type supporting sector 21 having disposed on its periphery a plurality of type forms 22. These forms extend parallel with each other and with the shaft 19, and are spaced from each other circumferentially of the type support 21, so that by the rotation of the type support on the shaft 19, the forms may be brought selectively and individually to a common printing line above the work bed 18.

For bringing the type forms selectively to printing position, each hub 20 has fixed thereon a radial arm 23, which extends through a slot 24 (Fig. 1) formed in the upper forward portion of the casing. Each arm 23 is provided with a convenient handle

25 and also with an index or pointer 26 adapted, during the movement of handle 25, to be brought into registry with a plurality of characters or symbols marked on a dial 5 27 adjacent thereto. Each of these characters on the dial corresponds with one of the type forms on the respective type support, and the dial characters and type forms are so arranged that when the index 26 is 10 brought into registry with a character on the dial, the corresponding type form is brought to printing position.

To retain the selected type forms in printing position, there is provided for each 15 type support a spring arm 27 fixed to the casing and serving as a detent for engagement with a series of notches 28 formed in a sector fixed to the type support, the notches being so arranged that when the type support 20 is moved to place a type form in printing position, the detent is centered in a corresponding notch in the sector, thus serving not only to hold the type form in adjusted position, but to accurately center it in such 25 position.

Any number of such type supports may be provided, there being seven in the present instance, and these supports may be provided with any system of type which are 30 suitable for selective combination to print a desired series of legends. In the present instance the machine is employed for printing amounts on commercial paper, such as checks, drafts and the like, and preferably 35 for printing such amounts in words rather than figures. Each type support therefore is provided with a series of words expressing the numbers indicated by the figures shown on the respective dials, and by selective movement of the type supports, suitable 40 words for printing any desired amount or monetary value within certain limits may be assembled in line with each other in printing position above the work bed. 45 These words, of course, are of varying length, as, for instance, the words "six" and "eighteen," as illustrated in Fig. 11, and therefore the type forms brought to the common printing line are separated by various 50 spacing distances in the direction of the line, as may be seen by reference to Fig. 1 where the type forms may be seen through the work receiving slot. In the impression made upon the work, however, the words 55 printed by these type forms are properly separated from each other by a small uniform spacing distance, as shown in Fig. 11, by a means and for a purpose later to be described.

60 The means for pressing the work against the type, and other related parts, are located in the base portion of the casing and will now be described. The work bed 18 has formed therein an elongated opening 29 (Figs. 2 and 5), in which is adapted to

move a reciprocating work support 30, preferably comprising a frame having a flat work receiving plate 31 flush with the work bed 18 and substantially of the width of the slot 29 in which it moves. The work bed 18 is provided at the sides of slot 29 with flanges 32 (Fig. 3), serving to guide the work support 30. The work receiving plate 31 has depending therefrom ends 33, formed with openings 34, in which are fixed the ends of a pair of sleeves 35 slidably supported on a pair of guide rods 36 extending longitudinally of the machine and fixed at their ends in the walls of the casing, thus providing bearings on which the work support 80 may be reciprocated from end to end of the machine with the work receiving plate 31 moving lengthwise of the slot 29 in the work bed.

The platen comprises preferably a relatively small roller 37 having trunnions rotatably carried in the ends of a pair of arms 38 fixed on a sleeve 39 pinned on the shaft 40, which is journaled for rocking movement in flanges 41 depending from the front 90 and rear of the work receiving plate 31. The arms 38 are extended on the opposite side of sleeve 39 and have rotatably carried thereby an inking roller 42. Shaft 40 is extended through an elongated slot in the front of the casing where it is provided with a convenient operating handle 43 rotatably carried on the end of the shaft, by means of which handle a reciprocating movement may be imparted to the work support 30. 100

During the reciprocating movement of the work support the platen and inking roll are adapted to be alternately raised through openings 44 and 45 respectively provided in the plate 31, this alternate raising of the platen and inking roller being brought about by a suitable rocking movement of the shaft 40, so that in one direction of movement of the work support the platen is raised against the underside of the work to 110 press the latter against the type forms above by rolling printing contact, while in the other direction of movement of the work support the platen is retracted and the inking roller is raised to ink the type. 115

The rocking movement of shaft 40 is preferably effected by a device comprising a pair of arms 46 fixed on a hub 47 pinned to the shaft 40 just inside the front wall of the casing. In the outer ends of the arms 46 120 is rotatably carried a roller cam follower 48 adapted to move during the reciprocation of the work support in a series of guide-ways or channels, indicated generally at 49 (Fig. 2), such channels being formed by 125 cam plates 50 projecting inwardly from a plate 51 fixed to the front wall of the casing. These guide-ways 49 comprise preferably neutral channels 52 and 53 at the ends thereof, with which neutral channels communi- 130

cate upper and lower channels 54 and 55 respectively. At the left end of the upper channel 54 (Fig. 2) is a switch 56 pivotally supported on a fixed bearing 57 and having an upwardly extending arm 58 to which is attached one end of a spring 59 having its other end fixed at 60 to the casing. Spring 59 normally holds switch 56 yieldably in lower position.

10 When the work support is at the left extremity of its movement (Fig. 2) roller 48 is in the neutral channel 52 in the position indicated by dotted lines. In this position the arms carrying the platen and ink roll 15 are in the neutral or intermediate position so that neither of these members is in operative position. Movement of the work support toward the right carries roller 48 into engagement with switch 56, by means of 20 which it is elevated into the upper channel 54, thereby lowering the inking roll and raising the platen to operative position, these parts being so arranged that the platen is raised to operative position just prior to 25 reaching the beginning of the first type form. As movement of the work support is continued toward the right, the platen presses the work against the type until roller 48 is carried by the formation of the channels 30 into the neutral channel 53 on the right, thereby lowering the platen just as it passes out of contact with the last type form. While the roller is in channel 53, both the inking roll and platen are again brought to 35 inoperative position. Movement of the work support toward the left carries roller 48 into the lower channel 55, thereby lowering the platen and raising the ink roll to position for rolling inking contact with the printing line of type, which operation continues until roller 48, raising switch 56, rides up into neutral channel 52, thereby placing the inking roll and platen in inoperative position. The operation of the above parts is 40 designed for the insertion of the work above the platen on the work receiving plate 31 when the work support is at the left extremity of its movement, and for the subsequent movement of the work support toward 45 the right to print the work, which is moved with the platen and the plate 31 until the work support reaches the right extremity of its movement, when the withdrawal of the platen allows the removal of the work, a 50 subsequent movement of the work support toward the left serving to ink the type in the manner described until the left extremity of the movement is reached when the parts are in position to receive a new piece of 55 work.

Means for supplying ink to the inking roller are provided comprising preferably an ink container or pad 61, carried in a channel or trough 62 extending longitudinally 60 of the machine and supported on a plate 63

supported at its ends by engagement with the guide rods 36. The arrangement of this inking pad is such that when the inking roller is moved to its lowermost position during the movement of the work support 70 toward the right, it will engage in rolling contact with the inking pad and receive ink therefrom.

Means for retaining the work on the receiving plate 31 and for feeding the work 75 during the movement of the latter, are provided comprising preferably a spring arm 64 extending forwardly above the work receiving plate and provided with a presser foot 65 formed in the forward end of said 80 arm and adapted to press the work against the receiving plate to frictionally hold it in place thereon. Arm 64 is further provided at its forward end with a stripper plate 66 comprising substantially a rectangular plate 85 having an opening 67 therein adapted to permit the work to be raised therethrough by the platen for contact with the type. The stripper plate serves to prevent contact of the work with the type forms above, except 90 under the action of the platen at the printing line and also to strip the work from the type immediately in rear of the platen during the movement of the latter.

Arm 64, as shown in Fig. 3, extends horizontally forward in the work receiving slot from a member 68 pivotally supported at 95 69 at the rear end of an arm 70 extending rearwardly from a substantially U-shaped member 71 having flanges 72 welded or 100 otherwise suitably secured to the bottom of the work receiving plate 31, member 71 embracing the platen supporting mechanism with openings in said member loosely receiving the shaft 40. The lower end of member 68 has a channel shaped portion fitting 105 slidably but snugly in a cam slot 73 formed in the plate 74 fixed on the casing. These parts are so constructed and arranged that the shape of the cam slot serves to hold the 110 presser foot raised when the work support is in starting position, permitting the insertion of the work but upon printing movement of the work support the presser foot is lowered into engagement with the work. 115 During such printing movement the presser foot is held in position to bear frictionally upon the work and when the platen has moved out of contact with the last type form the presser foot is again raised to permit the removal of the work. 120

The presser foot serves to retain the work on the receiving plate 31 of the work support so that the movement of the latter moves the work along the printing line. 125 When the platen moves into contact with the first type form, the engagement of the work between these parts holds the work stationary against the type, and presser foot 65 serves to permit relative movement of the 130

work and the work support, the work slipping over the receiving plate as the work support continues to move toward the right. (Fig. 2). As pointed out above, the type forms are assembled in the printing line with gaps or intervals of varying length between adjacent words or characters, owing to the varying lengths of the type forms and the manner in which they are supported. 10 As the platen passes these intervals in the printing line the work is released from the type, and the frictional engagement of the presser foot with the work serves to pick up the latter again and carry it along with 15 the work support until a subsequent type form is encountered by the platen, when the work is again held stationary in contact with the type until the platen encounters another interval or the end of the printing 20 line. The stripper plate 68 clears the work from adherence to the type closely in rear of the platen to facilitate the action of the presser foot. In this manner each of the 25 separate type forms in the printing line is impressed on the work by a rolling printing action of the platen, and the work itself is moved to compensate for the varying intervals in the printing line, the adjacent words or characters of the impression on the work 30 being separated from each other by a uniform spacing distance, as illustrated in Fig. 11.

The printing surfaces of the type and platen may be corrugated as indicated in 35 connection with the platen in Figs. 3 and 6 and in the impression in Fig. 11, so that they emboss or disrupt the fibers of the paper during the printing impression in order that the paper may readily absorb the ink 40 to increase the difficulty of erasing the impression. A construction suitable for this purpose is disclosed in the patent to Todd and Tiefel, No. 1,138,330, so that further description thereof herein is unnecessary.

45 A paper gaging and guiding device is provided in a bar 75 resting on the work bed 18 at the rear of the work receiving slot and having at its ends depending flanges 76 extending parallel with and in proximity 50 to the ends of the base portion of the casing. Fanges 76 are provided with elongated openings 77 embracing clamping screws 78 and 79, by means of which bar 75 may be adjusted forwardly or rearwardly on the work 55 bed and clamped in position suitable for receiving and guiding various sizes of work.

The operation of the machine will be clear after a brief explanation in connection with the above description of its construction.

60 The type for printing the desired legends having been brought to printing position by the selective manipulation of the handle 25, the gage 75 having been adjusted to suit the size of the work to be printed, and the work 65 support having been moved toward the left

by means of the operating handle 43, the work is inserted in the slot provided therefor, under the presser foot which is now in raised position, with the rear edge of the work against the gage and the point at 70 which the impression is desired to begin over the platen. Handle 43 is then moved all the way to the right, thereby releasing the presser foot to hold the work which is carried toward the right with the work support and impressed with the type by a rolling printing action of the platen. The yielding means provided in the presser foot for retaining the work on its support permits the work to be fed over its support while 75 it is being pressed by the platen against the type but serves to move the work with its support when the platen is out of contact with the type, as when passing intervals in the printing line, for the purpose of impressing the selected type forms on the work in alinement with each other and with a small uniform spacing distance between adjacent words. When the handle 43 reaches the right extremity of its movement, the 80 presser foot is automatically raised and the work may be withdrawn. Handle 43 is then moved to the left, during which movement the inking roll rises and inks the type and falls again when the work support reaches 85 the left hand position ready to receive a new piece of work. During each printing movement the inking roll comes in contact with its supply pad and obtains ink therefrom.

It will therefore be seen that the entire 90 legend is impressed on the work by a single printing operation of the operating handle and that the various type forms composing the desired legend, having once been selected, may be printed as many times in succession as desired with but a single printing 95 operation for each impression, the type forms being automatically inked between the impressions.

Having thus described my invention, what 100 I claim as new, and desire to secure by Letters Patent is:—

1. The combination with a type support and a line of type thereon; of a rotary platen adapted to be rolled along said line 115 of type to press the work thereagainst; a work support movable with said platen along the line of type; and work retaining means adapted to hold the work against movement relative to said work support 120 while the platen is out of contact with the type, but to permit movement of the work relative to said work support while the work is held in engagement with the type by the pressure of the platen.

2. The combination with a type support and a line of type thereon; of a rotary platen adapted to be rolled along said line of type to press the work thereagainst; a work support movable with said platen 130

along the line of type; and a presser member frictionally engaging the work to retain the latter against movement relative to said work support while the platen is out of contact with the type, but to permit movement of the work relative to said work support while the work is held in engagement with the type by the pressure of the platen.

3. The combination with a type support and a line of type thereon; of a rotary platen adapted to be rolled along said line of type to press the work thereagainst; a work supporting bed movable with said platen along the line of type; work retaining means for said work bed adapted to hold the work against movement relative to said work bed while the platen is out of contact with the type and to permit movement of the work relative to said work bed while the work is held in engagement with the type by the pressure of the platen; and automatic actuating means for said work retaining means for rendering the latter operative during the printing movement of the work bed, but inoperative at predetermined points in said movement to permit insertion and removal of the work.

4. The combination with a type support and a line of type thereon; of a work support movable longitudinally of said line of type, and carrying a rotary platen adapted to be rolled along the line of type to press the work thereagainst and carrying also a work retaining means adapted to hold the work against movement relative to the work support while the type and platen are out of contact but to permit movement of the work relative to the work support while the work is held in engagement with the type by the platen.

5. The combination with a type support and a line of type thereon, of a movable support for the work for moving the latter longitudinally of said line; and a rotary platen movable with said support for rolling, printing engagement with said line of type to effect an impression of the latter, on the work.

6. The combination with a type support, and a line of type thereon; of a work support movable longitudinally of said line of type for effecting a corresponding movement of the work; a rotary platen movable with said work support to press the work against the line of type by a rolling, printing contact therewith; and platen actuating means for moving the platen to operative position at the commencement of the impression and to inoperative position at the termination of the impression.

7. The combination with a type support, and a line of type thereon; of a support adapted to carry the work and movable in either direction longitudinally of said line of type; a rotary platen movable with said

work support, to press the work against the type by a rolling, printing contact therewith in one direction of movement of the work support; and an inking element movable with said work support, to ink said type in the other direction of movement of said work support.

8. The combination with a type support and a line of type thereon; of a work support movable in either direction longitudinally of said line of type, and having connected therewith a rotary platen, an inking roll, and a yieldable work retaining means, said work support being movable in one direction to effect an impression of the type on the work by rolling, printing contact of the platen therewith, and also to feed the work, and being movable in the other direction to effect a contact of the inking roll with the type to ink the latter.

9. The combination with a type support, and a line of type thereon; of a work support movable in either direction longitudinally of said line of type; a rotary platen carried by said work support and adapted during movement of the latter in one direction to press the work against the type by a rolling, printing contact; an inking roller carried by said support and adapted to ink the type during movement of said work support in the opposite direction; work retaining means for yieldably retaining the work on its support and permitting movement relative thereto while the work is held in engagement with the type by the platen; and operating means for moving said work support and for moving said platen and ink roller alternately to operative position.

10. The combination with a type support, and a plurality of type in alinement with and spaced from each other on said support; of a rotary platen having a rolling movement along said line of type to press the work thereagainst; and work feeding means adapted to feed the work along said line of type during said movement of the platen while the platen is out of contact with the type and to discontinue said feeding movement while the work is held impressed against the type by said platen.

11. The combination with a type support, and a plurality of type in alinement with and spaced from each other on said support; of a rotary platen having a rolling movement along said line of type to press the work thereagainst; and work feeding means, movable along the line of type with the platen, and adapted to feed the work as the platen passes a space in said line of type, and to permit the work to be held stationary in engagement with the type during the impressing contact of the platen with the type.

12. The combination with a type support, and a plurality of type in alinement with

and spaced from each other on said support; of a rotary platen having a rolling movement along said line of type to press the work thereagainst; and a work support 5 movable with said platen, including a yieldable work holding means for moving the work with its support along said line of type while the platen passes a space in said line, and for permitting the work to remain 10 stationary in engagement with the type and to move over its support during the impressing contact of the platen with the type.

13. The combination with a type support, and a plurality of type in alinement with 15 and spaced from each other on said support; of a rotary platen having a rolling movement along said line of type to press the work thereagainst; work feeding means adapted to feed the work along said line 20 of type during said movement of the platen, while the platen is out of contact with the type, and to permit the work to remain stationary in engagement with the type during the impressing contact of the platen with 25 the type; and work stripping means for separating the work from the type subsequently to the impression.

14. The combination with a plurality of type carriers, each provided with a plurality of type of varying length and movable to bring said type selectively to a common printing line; of a rotary platen having a rolling impressing movement along said line of type to print the latter; and work 35 feeding means adapted to move the work along said line of type with the platen while the latter passes an interval between adjacent type, and to permit the work to remain stationary in engagement with the type during 40 the impressing contact of the platen with the type.

15. The combination with a plurality of type carriers, each provided with a plurality of type of varying length and movable to bring said type selectively to a common printing line; of a rotary platen having a rolling impressing movement along said line of type to print the latter; work feeding 45

means adapted to move the work along said line of type with the platen while the latter 50 passes an interval between adjacent type, and to permit the work to remain stationary in engagement with the type during the impressing contact of the platen with the type; and inking means for applying ink to the 55 type.

16. The combination with a plurality of type carriers, each provided with a plurality of type of varying length and movable to bring said type selectively to a common 60 printing line; of a reciprocating device including a rotary platen, an inking roll, and a yieldable work holding means tending to move the work with said reciprocating device but adapted to release the work while 65 the latter is held in engagement with the type by the platen; and actuating means for moving the platen to position for rolling printing contact with said line of type when said reciprocating device is moved in one 70 direction, and for moving the inking roll to position for rolling inking contact with the type when said reciprocating device is moved in the opposite direction.

17. The combination with a plurality of type carriers, each provided with a plurality of type of varying length and movable to bring said type selectively to a common printing line; of a reciprocating device including a rotary platen, an inking roller, 80 and a yieldable work holding means; an ink supplying member; and actuating means for moving the platen to position for rolling printing contact with the type, and the inking roller to position for rolling contact 85 with said inking member, when said reciprocating device is moved in one direction, and also for moving said platen to inoperative position and said inking roller to rolling inking contact with the type when said 90 reciprocating device is moved in the opposite direction.
